J. W. HANGER.
CORNER AND END POST.
APPLICATION FILED AUG. 3, 1915.

1,188,171.

Patented June 20, 1916.

UNITED STATES PATENT OFFICE.

JAMES WILLIAM HANGER, OF MACY, INDIANA.

CORNER AND END POST.

1,188,171.

Specification of Letters Patent. Patented June 20, 1916.

Application filed August 3, 1915. Serial No. 43,391.

To all whom it may concern:

Be it known that I, JAMES W. HANGER, a citizen of the United States, and a resident of Macy, in the county of Miami and State of Indiana, have invented a new and useful Improvement in Corner and End Posts, of which the following is a specification.

My invention is an improvement in corner and end posts with wire tighteners attached, and the invention has for its object to provide a new and improved construction of corner and end posts, having wire tighteners attached and designed for permitting the ends of wire fencing to be connected to the posts in such manner that the fence will be held taut and upright, and may be retightened to compensate for any stretching that may take place.

In the drawings: Figure 1 is a front view 20 of one of the posts of a tightener attached, Fig. 2 is a top plan view of Fig. 1 and Fig. 3 is a partial perspective view of the post and tightener attached.

In the present embodiment of the invention, the fence is composed of horizontal wires 1, and vertical wires 2, the horizontal and vertical wires being interwoven or secured together in any suitable or desired manner at their intersection. The ends of 25 the horizontal wires of the line of fence are connected to a panel or plate 3 of suitable material, as for instance, metal or wood of sufficient strength, and each of the said plates or panels 3 has near one edge a series 30 of spaced openings 4 for engagement by the ends of the horizontal wires 1. The ends of these wires are passed through the openings 4, and are twisted around the body of the wire as indicated at 5, to prevent dis- 35 engagement of the said ends.

Each of the posts is of angle material as shown, consisting of integral portions 6 and 6^a, arranged at approximately a right angle with respect to each other and each 40 having at one end an integral web 7. The post is seated in the ground a sufficient depth, the end having the webs 7 being inserted in the ground, and the post is arranged with the portions 6 and 6^a parallel 45 with the planes of the respective strings or lengths of fence which they are to connect.

It will be understood that the improved post may be arranged either at the corner, 50 that is, the said posts may be used to connect two lines of fence extending at a right

angle or they may be used at the ends of a single straight line of fence. In the former case the portions 6 and 6^a of the post are parallel with the planes of the respective 55 lines of fence, but offset inwardly with respect to these planes in such manner that were the wires 1 of the strings extended they would pass outside of the portions 6 and 6^a of the post. In the latter instance, 60 the post is arranged with one of the portions bearing the above-mentioned relation to the line of fence.

When used at the corner the post is braced in both directions in the manner 70 shown in Fig. 1, that is, an inclined brace 8 is arranged between the post and a block 9, embedded in the ground. The upper end of the brace is secured to the post, 75 near the top.

An inclined strap brace 10 is arranged between the brace 8 and the post. A rod 11 is arranged between the outer end of the brace 8 and the portion 6^a of the post, this rod having at one end an eye 12, which engages 80 an opening in the vertical portion of the brace 8 near the block 9, while the other end is threaded and is passed through an opening in the portion 6^a and is engaged by a nut 13, on the outer face of this portion 6^a. 85 This rod 11 is just above the level of the ground, and the nut may be turned to tighten the brace rod 11 if desired.

It will be understood that where the improved post is arranged at the end of a 90 line of fence, it will be braced against the line and as a consequence when the post is arranged at the corner as shown in Fig. 2, where the second line of fence is designated at 1^a and 2^a, the post will also be braced 95 against this second line 1^a—2^a of fence, and in practically the same manner as it is braced against the line 1—2.

Each of the plates or panels 3 is provided in the opposite side edge from the openings 4 with a series of openings 14, and each opening 14 is engaged by an eye or hook 15 on one end of an eye bolt 16. The other end of each eye bolt is passed through the extended end of a plate 17, 100 which is secured to the post by rivets or the like. Each of these plates 17 to which the line of fence 1^a is connected is secured to the outer face of the portion 6^a of the post, and the plate is of such length 105 that it will extend transversely of this portion, and will extend beyond the portion at

the portion 6, and the extender end has an opening through which the extended end of the bolt is passed. A nut 18 is threaded on to the eye bolt at the outer face of the 5 plate, and it will be evident that when the nuts 18 are tightened, the plate 3 will be drawn toward the post. The plates 17 for the line of fence 1^a—2^a are secured to the outer face of the portion 6 of the post, in 10 precisely the same manner as the plates 17 on the portions 6^a.

In the present instance four bolts 16 are provided for each line of fence, and the openings 14 in the plates 3 of the two lines 15 are so arranged that they may engage their respective plates 17 with the upper end of the plate 3 flush with the top of the post. As many of the eye bolts 16 may be used as may be found advisable, but with a fence of 20 ordinary height four bolts are sufficient to hold the fence firmly in place.

In use, the post being seated and braced as shown and described, the bolts 16 are passed through the openings in the plates 25 17 and each bolt is engaged by its nut 18 to hold it in place. Commencing now at either end, the nuts 18 are tightened, until there is sufficient tension of the wires 1 and 1^a. The fence is now complete, and should there 30 be sagging for any reason this may be compensated for by turning the nuts 18 in the proper direction. The braces 8 and 10 are

bolted to the post, and the rods 16 are threaded throughout practically their entire length in order to permit the greatest possible amount of adjustment. 35

I claim:

Means for stretching two sides of an inclosing fence at the corner, the same consisting of a fixed angle post disposed with the angle formed between the wings facing inward, plates attached to the outer face of one of the wings and projecting outwardly beyond the outer face of the second wing, other plates secured to the outer face of the 40 second wing and projecting beyond the outer face of the first mentioned wing, the projecting ends of the two sets of plates having openings, two bars having the ends of the respective sides of the fence attached thereto, longitudinally movable tensioning members mounted in the apertured ends of the two sets of plates and connected at their inner ends to the respective bars, and means 45 coacting with the outer ends of the tensioning members and with the apertured ends of the respective plates for moving the bars and stretching the two sides of the inclosing fence. 50

JAMES WILLIAM HANGER.

Witnesses:

KARL B. GAST,
NATHAN PERRY.
